UNITED STATES PATENT OFFICE

167,645

TEAPOT OR SIMILAR ARTICLE

Charles H. Newman, Northfield, and James L. Hvale, Chicago, Ill., assignors to Teamakers, Inc., Chicago, Ill., a corporation of Illinois

Application April 26, 1952, Serial No. 19,488

Term of patent 14 years

(Cl. D44—25)

To all whom it may concern:

Be it known that we, Charles H. Newman and James L. Hvale, both citizens of the United States of America, and respectively residing at Northfield and Chicago, county of Cook, State of Illinois, have invented a new, original, and ornamental Design for a Teapot or Similar Article, of which the following is a specification, reference being had to the accompanying drawing, forming part thereof.

Fig. 1 is a side elevational view of a teapot or similar article, showing our new design.

Fig. 2 is a similar view of the article when turned from right to left through an arc of 90 degrees about its upright axis relative to the position thereof shown in Fig. 1.

Fig. 3 is a top plan view thereof.

We claim:

The ornamental design for a teapot or similar article, as shown.

CHARLES H. NEWMAN.
JAMES L. HVALE.
